UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

SURFACE-CONTACT STRUCTURE.

SPECIFICATION forming part of Letters Patent No. 713,015, dated November 4, 1902.

Original application filed October 11, 1897, Serial No. 654,793. Divided and this application filed February 28, 1901. Serial No. 49,220. (No model.)

To all whom it may concern:

Be it known that I, WILLIAM B. POTTER, a citizen of the United States, residing at Schenectady, county of Schenectady, State of New York, have invented certain new and useful Improvements in Surface-Contact Structures, (Case No. 2,104,) of which the following is a specification.

This is a division of the application for patent, Serial No. 654,793, filed October 11, 1897, and the invention relates to a novel construction of surface-contact stud adapted for use in sectional-conductor electric railways.

The drawing is a vertical section of the entire structure, showing the stud itself in elevation.

It is important in structures of this character that the stud should be securely mounted in its operative position, so that it will not be disturbed or rendered inoperative by heavy city traffic and the engagement of collector-shoes, and at the same time that the stud should be adapted for ready removal when its upper surface is worn or it is damaged in any respect. Furthermore, it is especially important that the stud should be in good electrical contact with the lower connections or leads, and this contact should be such that the stud can be readily removed for the purpose of inspecting the connections.

In the drawing the stud R is shown in elevation and as having an enlarged head or button H, which is exposed in the roadway and adapted to be engaged by the collector of the car. The entire stud, with the exception of the exposed upper surface and lower projection, is embedded in or surrounded by a body of insulation S, such as vitrified brick. The stud and insulation together are adapted to be moved and replaced independently of all other parts of the structure.

P represents a suitable metallic tie, on which is mounted a receptacle T by means of bolts B, in which receptacle the block of insulation S is held by suitable material C, such as cement. The roadway is built up around the block S, so that only its upper surface is exposed, and when it is desired to remove the stud the block S is simply loosened in the receptacle T and lifted up.

Suitably located, as in a compartment formed by the metallic tie P, is an insulating-base Q, formed with an upper opening of two different diameters. A metallic support Q² rests on the shoulder formed in the upper opening of the insulating-base, and to this support are secured the flanges F of a contact-sleeve Q'. This sleeve Q' is adapted to receive the depending projection R' of the stud R, and its upper edge O is made flaring, so that the projection R' will be properly guided into the sleeve when the block S is inserted in the receptacle T. The sleeve is split, as shown at L, in order that it may expand when the projection R' enters it and hold the projections with a spring-grip in good electrical contact. The lower flanges F are secured to the support Q' by means of bolts M, the heads of which are located in the portion of the upper opening in the insulating-base Q which has a small diameter. The right-hand bolt and nut, which hold the flange to the support, also constitute a binding-post for the lead I, which completes the circuit connection of the stud. It will thus be seen that when the stud R, with its surrounding insulation S, is inserted in the receptacle T its lower projection R' will engage the upper flaring edge O of the split sleeve, so that the projection R' will be guided centrally in the sleeves and will be held therein with good electrical contact. Whenever it is desired to remove the stud when its upper working surface is worn or the stud is otherwise inoperative, it can be removed to automatically break the contact of the stud with the lead I. A further advantage of the ready removability of the stud and its insulation is that it leaves the lower connection parts in full view for the purposes of inspection or repairs.

What I claim as new, and desire to secure by Letters Patent of the United States, is—

1. In a removable surface contact, a metallic stud surrounded by insulating material, in combination with a support, a terminal secured beneath said support, and a projection on the stud arranged to make electrical contact with said terminal.

2. In a removable surface contact, the com-

- bination of a metal stud having an enlarged head, molded insulating material surrounding the stud, a metal base for the insulating material adapted to be bolted to a cross-tie, a terminal secured within the tie and connected to the source of supply, and a projection on the stud arranged to make electrical contact with the terminal. 5
3. In a removable surface contact, the combination of a central metal stud having enlarged ends, insulating material around the stud, a metal base for the insulating material bolted to the cross-tie, an insulating terminal support secured to the cross-tie, an upwardly-extending contact carried by the support, means for securing the lead from the source of supply, and a projection on the stud arranged to establish connection with the contact. 10
4. A surface-contact stud having integral enlarged ends, and having insulating material molded about it, so that only its two ends project from the insulation. 15
5. In combination, a hollow split metallic sleeve, and a surface-contact stud removably mounted therein. 20
6. In combination, a hollow split metallic sleeve, a surface-contact stud having insulating material molded about it, so that only its two ends project, the lower end being adapted to engage in the hollow sleeve; and a separate support for the insulating material. 25
7. A single removable structure for surface-contact railways, which comprises a contact-stud having enlarged ends and its surrounding insulation, said insulation being molded about said stud. 30
8. A surface-contact stud surrounded by insulating material and projecting downwardly therethrough, in combination with means for connecting the projecting portion with the circuit-lead and an independent support for said connecting means. 35
9. The combination with a removable surface-contact stud, having integral enlarged ends embedded in insulating material, of a lead carried out from the bottom. 40
10. In combination with a surface-contact stud, a terminal which comprises a hollow split metallic sleeve, and a lead secured thereto. 45
11. In combination with a surface-contact stud, a terminal which comprises a hollow split metallic sleeve having a flaring upper edge. 50
12. In combination with a surface-contact stud, a terminal which comprises a hollow split metallic sleeve provided with flanges, and a base-plate to which said flanges are secured. 55
13. A terminal for a surface-contact stud, which comprises a hollow split metallic sleeve provided with flanges, a connecting-lead, a base-plate, and means for securing said parts together. 60
14. A terminal for a surface-contact stud, which comprises an insulating-base, and a metallic sleeve secured thereto, and adapted to receive the lower end of the stud. 65
15. A terminal for a surface-contact stud, which comprises an insulating-base, a metallic support thereon, and a metallic sleeve having flanges which are secured to said support. 70
16. In a removable surface contact, the combination of a stud of conducting material surrounded by insulating material and having its ends projecting therefrom, of a terminal comprising a split metallic sleeve provided with flanges, a connecting-lead, a base-plate, and means for securing said parts together. 75
17. In a removable surface contact, the combination of a stud of conducting material surrounded by insulating material and having its ends extending therethrough, a support for said insulating material and stud, a terminal adapted to receive one end of said stud, and a separate support for said terminal. 80
18. In witness whereof I have hereunto set my hand this 25th day of February, 1901. 85
